[57] **CLAIM**

The ornamental design for a hanger rack for garments or the like, substantially as shown and described.

DESCRIPTION

FIG. 1 is a perspective view of a hanger rack for garments or the like showing my new design;
 FIG. 2 is a front elevational view thereof;
 FIG. 3 is a back elevational view thereof;
 FIG. 4 is a side elevational view taken from the left of FIG. 1;
 FIG. 5 is a side elevational view taken from the right of FIG. 1;
 FIG. 6 is a top plan view thereof;
 FIG. 7 is a bottom plan view thereof;
 FIG. 8 is a perspective view of a second embodiment of the design of FIG. 1;
 FIG. 9 is a front elevational view of FIG. 8;
 FIG. 10 is a back elevational view of FIG. 8;
 FIG. 11 is a side elevational view taken from the left of FIG. 8;
 FIG. 12 is a side elevational view taken from the right of FIG. 8;
 FIG. 13 is a top plan view of FIG. 8;
 FIG. 14 is a bottom plan view of FIG. 8;
 FIG. 15 is a perspective view of a third embodiment of the design of FIG. 1;
 FIG. 16 is a front elevational view of FIG. 15;
 FIG. 17 is a back elevational view of FIG. 15;
 FIG. 18 is a side elevational view taken from the left of FIG. 15;
 FIG. 19 is a side elevational view taken from the right of FIG. 15;
 FIG. 20 is a top plan view of FIG. 15;
 FIG. 21 is a bottom plan view of FIG. 15.
